UNITED STATES PATENT OFFICE.

MARY A. E. HACKETT, OF NEW YORK, N. Y.

DESIGN FOR A HAT-PIN.

SPECIFICATION forming part of Design No. 27,649, dated September 21, 1897.

Application filed August 13, 1897. Serial No. 648,175. Term of patent 14 years.

To all whom it may concern:

Be it known that I, MARY A. E. HACKETT, a citizen of the United States, residing at New York city, in the county and State of New York, have invented and produced a new and original Design for a Hat-Pin, of which the following is a specification, reference being had to the accompanying drawing, forming a part thereof, in which is represented a side elevation of the pin embodying the features of my design.

The pin is designed to readily pass through the hair and yet be retained therein, so that the pin may be readily placed in position on the head and afterward readily entered into the hat at opposite sides.

The design consists in forming the pin with a long practically straight member A, a second shorter and substantially straight member B, and an intermediate or intervening bow or arched member C, the outer ends of the two members A and B being pointed.

I claim—

The design for a hat-pin herein shown and described.

MARY A. E. HACKETT.
